James Stimpson
Litter Patent

The Schedule referred to in the following Patent and making part of the same, containing a description in the words of the said James Stimpson himself of his improvement in the mode of ascending and descending Rivers and Canals or inclining planes, using such Steam Engines or other locomotive power on board as well as the respective vehicles to be moved as may be found necessary for this ascent or descent.

To all whom these Presents shall come

Be it known, that I, James Stimpson of the City and County of Baltimore, and State of Maryland, have invented a new and useful improvement in the mode of ascending and descending Rivers and Canals or inclining planes on which locomotive engines, among other kinds of power, steam, animal, may be used on board as well as the respective vehicles thereon; and that the following is a full and exact description of the said invention or improvement as invented or improved by me, to wit: Firstly as to the mode of passing over inclining planes, when the nature of the country over which it is intended to build Rail Roads, is such, that a road must be laid on inclining planes, to sufficient elevations over which they must pass, and that is so abrupt a manner that the power of locomotive engines, or other persons, or the adhesion of the wheels to the iron plates on which they run, would be inadequate to enable them to surmount said elevations, more especially when it is combined with snow, frost, ice or water; I propose to use chains of any kind, which may be found most convenient, such as chains used for ships' cables, or any other that may be preferred; in the following manner, take one or more such chains, stretch them somewhat tight, and make them fast at both ends to something that is firmly fix'd in the earth near the foot and top of the inclines; and so placed that the said chains may lay their whole length upon the ground, or upon such other supports as may be provided; and on one or both sides of the tracks or in its centre as may be preferred; the links of the said chains should be uniform in length and width, or very nearly so; also propose to have for carriages which are used as towing, carriages or when passing, only by themselves, when they have the power of motion within themselves, a ship, or change gear, that the operative power may be changed from the immobi-

are contract with the road-wheels of said carriages, to that of a pulley shaft or any other application desired, for the same object, which pulley shaft may be placed whereto the car is in front of the road-wheels, or between them or anywhere else that may be found the most convenient for it which shaft may have several sets of pulleys side by side upon it, at each end, or if the chains are laid in the centre of the vehicle, and sufficient room can be had beneath the bottom of the car, or over it, for its easier that place or situation, the pulleys may then be fastened upon said shaft in the middle, or centre, which pulleys may be of as many and various sizes as there may be variations of vessels in the different carriages to be passed over, and be all made fast to said shaft side by side of each other, the like number upon each end of said shaft, if for two chains, but if for one chain only, and that in the middle, then one set of pulley will be sufficient; said pulleys should only occupy as much room in the carriage, as is necessary for their proper strength; and to receive the chains in the centre of their peripheries, having a thin flange between each end on each side of them to serve as a guide to the chains, said pulleys should be made of cast iron or other metal, and be cast in two pieces flat ways, each separated in their centre with the flange upon the side opposite to that which is to join when put together. The former size of one half of the chain which may be used, must be indented and surrounded by cast iron the edge of the peripheries of said pulleys between the flanges so that when two of said pulleys shall be put together upon the shaft, with the flanges on the peripheries of said pulleys between the flanges, will then have cavities or wells of the form and size just right to receive the links of said chains; one link lying flatways in a well sunk nearly or quite its whole depth more or less, below the surface of the peripheries of said pulleys, the next link upon particularly, the next flat again, and so on alternately throughout this whole surface. Also for power to have a set of small pulleys centered upon one end of a board that they may be raised or depressed plowmen by the means of said board, and to be placed immediately over and down upon the first named pulley, but only as thick upon their peripheries as to nearly cover the space between the flanges of those first described; the last mentioned pulleys must have a groove and channel in the centre of them, all round, which channel must be of sufficient width and depth to receive the links of the chains which may lay in the under pulley's edge ways, or up and down, the surface of the peripheries on each side of said channel should run upon the links which lay flat ways.

lever on which the pulley now should be contrived a proper distance from said
 pulley, upon a fixture attached to the carriage, so that said lever having a fixed
 leather or catch or fall attached to it may when the aforesaid chain is to be placed
 upon the aforesaid under pulley be raised up to allow said chain to pass in be-
 low it and then forced down again close upon the chain and be held by the
 aforesaid catch or fall, thus the perpendiculars of the upper pulley run upon the chain
 and lie upon their own shaft and pivot by contact merely with the chain
 holding it down in the cells in the under pulley, to prevent its rising, slipping,
 wandering, or the aforesaid under pulley may have with or any other contriv-
 ance whereby to hold fast to said chain. These pulleys should lay as near to
 the ground as may be with safety. To use this improvement when you arrive with
 a car at the foot of an incline plane, you will stop and place the chain between
 the pulleys, change the power from the road wheels to that of the pulley shaft;
 and supposing that the road wheels are three feet diameter, and the inclination of
 of the incline plane about to be ascended is such that the opposition to motion by
 gravity is just equal to all the friction, or that the opposition to motion now subsi-
 on the plane or level road, or in other words, if the gravity add to the friction
 is such as to require just double the power it did to travel the level road, then
 then put the chain upon a pulley of eight or nine feet diameter, that being half of the
 size of the road wheels, the same engine or power used upon the plane will suffice
 you to ascend the incline, as there is no loss of power or increase of friction in any
 degree, the chain being merely raised in front and kept again behind as fast as the
 engine runs upon the road, it is in perfect balance over the pulley with itself all the
 while, and as there is no rendering movement of the chain upon the ground, to be con-
 sidered, there can be no loss of power, but the power in this case will be diminished one
 half during its ascent; when you have arrived at the summit of the incline on
 a little快要, cast off the chain upon the ground, change the power back again
 to the road wheels, and go on as usual. Again suppose there should be three sets of
 inclines all necessarily differing one from the other in the angle of their inclination, and
 that it would be desirable to pass the whole of them with the same engine, than there
 should of pulley, side by side permanently, fixed upon the same shaft as before de-
 scribed, each of a size sufficient for the different inclines to be passed over. Thus the
 whole length of the road may be travelled with the same power, and that also

independent of the adhesion of the wheel to the rail. Any further degree of power, independent of the size of the pulleys to that of the road wheel may be acquired by, placing a large one on the pulley shaft and a small one on the crank shaft which, latter is to drive the first named. The necessary change of the power from the road wheel to the pulley shaft can be in the locomotive engine, or any other kind, of carriages, may be accomplished in various ways, but the following may suffice as an, which will answer, and which stand present. When roads are crooked and much power is desired it will be necessary to use gears, hence two gear shafts and wheels will be already provided for our purpose, another upon the aforesaid pulley shaft, with that will be necessary provided the crank shaft that receives the power from the engine or other power is so constructed that it can be made to slide sufficiently to change the contact of the cog or teeth of the wheel on the crank shaft, from the position or contact on the road wheel, aptly to that of the aforesaid pulley shaft, whereby the object will be accomplished, and as the necessary movement required is but about two and a half inches, it can be done with safety, by lever or screw, or any other way which may be desired, the bogs or pillow blocks in which the crank shaft revolves may be connected to long wide iron plates fitted close down upon permanent rail or fixtures, which plates we will call slide plates, and we shall make such, and so wear them, that lateral movement we will have, starts or ears projecting from the permanent rail close to the outer edges on both sides and within about six inches of each end of said slide plates, there should be two levers wide enough at the place where centered to cover said slide plates, the handle on as splicing, by each other to a convenient length, said bars to be centered in or upon the aforesaid starts or ears, with a wedge from under from the under side and at the end of said levers, which wedge is to pass down between said plates and a permanent start or fixture to the permanent rail, said wedge to be thick enough to make the necessary movement for the change of the gears, the same at both ends of said plates, there must also be a start within the center of said levers, underneath, extending the whole width of a three inches, more or less, continuing on to the object of which is that when said lever handle is thrust down sufficient to raise the aforesaid wedge to allow said slide plates to move its proper distance, and that immediately after the aforesaid start is descended the lever is to spring down and hold fast, that

that end of said slide plate, the handle and said lever may be sprung under a spring catch whereby to hold it securely. It will now be seen that the handle end of this lever is down and binding said slide plates at that end firm upon the rail or its bed underneath and that the wedge is out, also it should be understood that the opposite lever at the opposite end of the aforesaid slide plate at the wedge, or its outer end is down and that its wedge is firmly seated between the end of the slide plate and the permanent fixture upon the rail and at the same time the under edge of said lever just within the wedge, by a nail or staple or projection should come in contact with the upper surface of the aforesaid slide plate, and by a spring catch or spring, underneath the handle end of said lever, bind down on both said slide plates as before set forth at the opposite end, thus it will be seen that by casting off the aforesaid spring catches, or props, the levers become loose, and also the slide plates beneath them, except one which until the levers are loose is not to be held from by the wedge, and that by lowering the handle end of the lever that was up, it will raise the wedge at the opposite end and thereby permit the slide plate to move that way, namely raising the handle end of the opposite lever it will thrust down its wedge and cause said slide plate to move the opposite way, and at the same time causing it to move in a longitudinal way, and then by passing the handle under the spring catches, &c it will be confined every way, thus the aforesaid levers are made to move the aforesaid slide plates, whereby a change of gear is effected, and at the same time, serve as levers to hold said slide plates as occurs as in any other way. The same application as herein set forth or a separator must be applied at the opposite end of the aforesaid crank shaft. The handle ends of the aforesaid levers which are abreast of each other transversely of the carriage, may be connected by a bar which will afford the means of moving the slide plates on each side of the carriage simultaneously, or the aforesaid movement of the crank shaft by that of the aforesaid slide plates may be effected by wedges or keys to be acted upon as aforesaid by levers, or any other ways, these wedges acting passing the outer end of the boxes in which the journals of the shaft revolve through the cap and bed between which, said boxes are confined and the pillar blocks emitting thereby the slide plates altogether. The chief objection to the aforesaid movement of sliding the crank shaft is that of its connection to the eccentric motion which operates the steam

6

Means and places whereto in this case must necessarily be applied in another way, or
 performed upon some other shaft so placed as to avoid it of the change, or the vari-
 ation may be performed by the connecting rod, by its turning two centres among other
 rough. I also propose another mode, which may be effected as follows; by this
 shaft upon the crank shaft thick about the eye and loose upon said shaft.
 Let stars or knobs be cast upon the inside of the rims of said wheels, thereby upon
 said shaft between said wheels, a slide coupling so made that it cannot turn up
 on said shaft without turning it, but can move side ways, said coupling may
 be in form of a blank wheel, with stars or knobs projecting each way, which stars
 or knobs should be made so as to mesh in between the first named stars upon the
 inside of the rims of the two gear wheels, having a groove in said slide coupling
 in which the end of a lever must be fitted whereby to move said coupling up
 to either of said wheels, the stars upon each will intersect each other, by this
 means this wheel becomes a fixture to said shaft and cannot turn round
 without said shaft turns with it, the coupling being of itself a fixture to
 said shaft, in which situation of said coupling it is wholly disengaged from
 the other wheel. And we will suppose, that this wheel now made fast as afor-
 said is in contact with the shaft upon the before mentioned pulley shaft,
 and thereby, that shaft in motion, the other wheel upon the crank shaft
 upon the opposite side of the slide coupling, is in contact always with the
 wheel upon the road wheel axle, but that being disengaged from the cou-
 pling is entirely free to turn loose upon the crank shaft, which causes no other
 friction than simply its moving upon said crank shaft, the wheel itself
 performing no operation at that time; all the working being performed by the
 pulley shaft where the other is loose, change the coupling to intersect the wheel
 in contact with that on the road wheel axle and the carriage will be moved
 by the revolving of the road wheels and their adhesion to the rail, so that
 in this case the pulley shaft will lay still, the wheel on the crank shaft
 becoming, or being, of itself loose upon said shaft. The aforesaid change of
 gears, or the power from one object to the other, may be effected as follows;
 Placing one gear wheel upon the road wheel axle, one upon the crank shaft,
 and upon the pulley shaft, all in range of each other, taking care that the
 wheel upon the crank shaft does not touch either the one upon the pul-
 ley

by shaft, or that upon the road wheel axle at any time, and also that these be permanently fixed in their several places, then centre a fourth wheel upon the short end of lever, so placed as always to be in contact with the crank shaft gear, and by this means of the lever made to connect one foot ultimately with the gear upon the pulley shaft or that upon the road wheel axle, and thus by its change from one to the other, the pulley shaft and the road wheel axle may either of them be made to revolve at pleasure, or it may be done in any other way. I also propose in the same way, or by any other means to effect various speeds or progress from the same crank shaft, with gears, in a similar way, only varied in size, for instance, let there be two or three sized wheels placed fast upon the road wheels axle, the first with twenty teeth, the second with thirty, the third with forty, also place the same numbers of wheels upon the crank shaft loose, never varying size to those on the road wheels axle, all connecting together at the same time making either of them fast upon the crank shaft by the aforesaid slide coupling, or bayonets or any other way, the speed of the carriage will correspond to the proportions of the variation between the driver and the driven, and thus when the smallest wheel upon the crank shaft is made fast by the coupling or bayonets, that wheel of course meshing with the largest upon the road wheel axle, they having the one say twenty, and the other forty teeth, it will require two revolutions of the crank shaft to produce one revolution of the road wheel, hence you may ascend inclines where the adhesion of the wheels are sufficient, but would otherwise lack power to move a load that the same power would draw upon four shafts nine-tenths the weight of the one which are suppose there are no inclines, hence with this application a full load may be moved the whole length of a road which would be in money again costing only a part of the space from tenth of the distance, and permitting one third or one half more to be drawn with the same power over the entire route, and during high ad a case winds a constant motion may be kept by using the variable power or speed as aforesaid when without them you might be compelled to stop or abandon part of the load or greatly overstrain the boiler. Then by these variable gears powers, and speeds, and the application of the pulley shaft and chains, in chains of almost any description may be

provided over with batteries that would be full for the engines upon the level road, which finally, accomplishes with the least possible expense all that has been done by locomotives and stationary power, at a cost of $\frac{1}{4}$ part of the power when passing inclines, which comparing time with power is a gain, for in the first place a train, the locomotive power will be working constantly with its whole power in any, or all situations, whereas the stationary power would necessarily be idle more or less of the time, although kept ever ready for usual great expense and when used being surrounded with ropes or chains, which it has to draw over a long distance, thereby, requiring a great power, notwithstanding, such ropes or chains may be supported by friction rollers, the whole length of the incline an expensive arrangement which by the improvement have prepared without any expense with.

Secondly, I also propose to supply the said improvement, to own board of the boats, with chains and pulleys as aforesaid, for the use of towing boats or vessels of any kind, in rivers and canals elsewhere, by the means of machinery, or otherwise, strain among other power, as follows to the said pulleys, and they, acting upon the chain as aforesaid, said chain should be made fast to each end to such fastness, and in such suitable places on the river, canals, bays, Harbours, and elsewhere, as shall be deemed most convenient and useful, and to lay upon the bottom of each river, canals, bays, Harbours, No under the water, or on any kind of support which may be foreseen, then may be the chain one to draw by in one direction, and the other chain in the opposite direction, over only may be used, with a general understanding that those passing, in one direction, when meeting a vessel, shall let go the chain upon a take it up again, said chain may be made fast by hooks or otherwise, to ring bolts in the bottoms of boats or such other fastness as shall be preferred, and in as many different lengths or places as shall be found necessary, in this case the power must be own board of the towing vessel and it should be applied direct to the aforesaid pulley shaft, no change of speed or proportion being required, as in planes and inclines, or it may be in any other way, This application of power in tow boats or vessels acting upon the chain as aforesaid, will draw up the weight of the tow boats, thereby, saving the banks of said canals, rivers &c, and allowing them to be used for rail roads and other purposes.

17. The aforesaid pulley shaft may lay athwart the road with pulley upon each end as before described, and of such size, as shall produce a speed compared with that of the animal, horse, or other power, or may be stronger or more useful, if animal power be used, it may be upon horizontal wheels, or moveable floors such as I use for my patent horse power carriage upon rail roads, or in any other way desired.

What I claim is any invention or improvement in the application of chains to ascend and descend, from Rivers and canals, or in elevated places, or rail roads, or otherwise, said chains being made fast at both ends near the foot and top of the inclines, and resting upon the ground or other material or at suitable places in Rivers or Canals, the locomotive or other engine, drawing themselves up or letting themselves down said inclines River or Canals, by the power which is on board of themselves, by the agency of pulleys in contact with said chains as set forth in this Specification, or in any other way, also the variable speed, or powers herein set forth, or in any other way, for the locomotive or itself moving carriages upon rail roads, not using the chain, I also claim the application of machinery to change the moving power from the road wheels of locomotives upon rail roads where the inclination is too much for the adhesion of the wheels to the rail plates to allow them to ascend or descend, without slipping, or sliding upon said rails, to a pulley shaft as aforesaid, or any other thing, whereby said power is used in a different manner than in immediate contact with the road wheels or their axles as set forth in this Specification or in any other way.

Witnesses.
